[57] ABSTRACT

Apparatus for testing a well packer having a supporting body anchored to a surrounding well conduit and

on which is carried a seal member for forming a fluid-tight seal between the surrounding well conduit and the supporting packer body. The testing apparatus may comprise an inner well conduit concentrically disposed within the surrounding well conduit and to which is attached a tubular mandrel for disposition within the supporting packer body to form an annular flow passage in fluid communication with the annulus between the two well conduits. Annular pack-off means comprising a cylindrical sleeve member is carried by the mandrel for axial movement from a first position above the annular passage to a second position sealingly engaging this flow passage and preventing flow of fluids from the annular passage through the annulus between the well conduits. The sleeve member may be mounted on the mandrel for limited axial movement relative thereto and may be initially prevented from axial movement relative to the mandrel by hold-down means. The hold-down means may be adapted to release the sleeve member in response to pressure applied to one end thereof so as to permit its limited axial movement relative to the mandrel. The hold-down means also includes cooperable friction means on the mandrel and the sleeve member responsive to pressure applied to the opposite end of the sleeve member to permit axial movement in one direction while restricting movement in the opposite direction.

WELL PACKER AND TESTING APPARATUS

BACKGROUND OF THE INVENTION

1. Field of the Invention

The present invention pertains to well packers and apparatus for testing the sealing of well packers with a surrounding well conduit. The invention is particularly directed to an improvement for assuring a proper seal between the sealing element of a gravel packer and the surrounding well conduit.

2. Description of the Prior Art

Gravel packing is a procedure employed to form a filter body in the annulus between the wall of a relatively unconsolidated oil producing formation in a well bore and the production pipe. Normally the latter includes a section of pipe, commonly termed a liner, having a plurality of narrow spaced apart apertures or having screen covered openings through which the formation fluids enter the production pipe from the formation while the gravel body interposed between the liner and the formation walls serves to support the unconsolidated formation and, at the same time, aiding in screening out fine sand and the like from the fluids, so that clean fluids may enter the production pipe.

Until a few years ago gravel packing tools have comprised separate liner setting tools and gravel placing devices which are relatively complicated in form and subject to various types of difficulties in setting in place in the well bore and in conducting the gravel packing operation. In recent years simplified assemblies have been developed which include a liner hanger and packer, as well as a gravel packing tool, all combined into compact easily operated and efficient gravel packing assemblies. Some of these assemblies are provided with a cross-over arrangement in the gravel packing tool by which fluid may be selectively circulated through the tubing or inner pipe string to the annulus below an intervening packer seal or in the reverse direction from the annulus to the tubing string. Some of these assemblies also provide a hydraulic pressure actuated liner hanger in combination with a packing seal for the well bore in which the cross-over arrangement may be used to selectively deliver actuating pressure fluid to the liner hanger and washing fluid to the production formation, as well as gravel carrying fluid for packing the annulus between the formation and the liner.

Such a tool and packer assembly is disclosed in U.S. Pat. No. 3,072,204 issued to Cicero C. Brown on Jan. 8, 1963. The gravel packing assembly described in that patent is provided with ports between the inner and outer strings and sleeve valve arrangements which are operable for controlling the ports during the conducting of the several stages in setting and releasing of the gravel packing tools and in conducting the gravel packing operation. Although such an assembly offers many advantages over separate liner setting tools and gravel placing devices, there are some objections to its use. For example, such an assembly does not provide a means for testing the seal established between the packer seal and the surrounding well conduit. It is extremely important that a fluid tight seal be established between the packer seal and the surrounding well conduit. Otherwise, fluids may leak past the packer.

SUMMARY OF THE PRESENT INVENTION

The present invention is directed to an improvement

in a combination well packer and tool assembly such as is described in the aforementioned U.S. Pat. No. 3,072,204 specifically designed for more easily and efficiently conducted gravel packing operations. In particular the improvement is directed toward providing a means by which the seal between the packer and surrounding well conduit may be tested to assure a fluid-tight seal. Another object of the invention is to provide a means by which additional forces may be applied to the packer seals to assure sealing under all conditions. Although the testing apparatus of the present invention was primarily designed for use with such a gravel pack arrangement, it is not so limited. It may be used with other well packers to test the sealing engagement of such a packer with the surrounding well conduit.

In summary, the apparatus of the invention comprises a tubular mandrel which may be attached to an inner well conduit or tubing string for disposition within a surrounding supporting body forming a portion of the well packer. An annular flow passage is formed between the supporting body and tubular mandrel to provide fluid communication from a point below the packer seal and the annulus between the outer and inner well conduits. An annular pack-off means is carried on the tubular mandrel and is axially movable from a first position above the annular flow passage to a second position sealingly engaging the flow passage preventing flow of fluids between the annulus surrounding the inner well conduit and the bore of the well beneath the packer seal. Thus the annulus between the inner and outer well conduits may be pressurized to check the packer seal. If there is a leak it will be detected by an increase in pressure or fluid flow through the inner well conduit.

The annular pack-off means may comprise a cylindrical sleeve member which is mounted on the tubular mandrel for limited axial movement relative thereto and which is provided with an annular seal for engaging the supporting packer body within the annular passage bounded thereby. The sleeve member may be affixed to the mandrel by hold-down means which includes a retainer device responsive to pressure applied to one end of the sleeve member to affect its release to permit limited axial movement relative to the mandrel. With such an arrangement additional forces may be applied to the packer seal for assuring fluidtight engagement with the surrounding well conduit.

The pack-off means may be displaced from the annular passage by applying pressure to the lower end thereof through the inner well conduit, allowing further operations to be conducted. The hold-down means may comprise cooperable friction apparatus on the mandrel and sleeve member permitting the sleeve member to be displaced from the annular passage and preventing its reengagement therewith.

Thus the invention provides an improved well packer and tool assembly which allows the packer seal to be tested prior to conducting further operations. This is extremely important in gravel packing since it is sometimes difficult and expensive to remove a non-functioning packer after gravel placement. In addition to providing a means for testing the packer seal, the present invention provides a means by which the packer may be more firmly anchored within the well conduit and by which the packer seal may be assured of greater sealing forces. Other objects and advantages of the invention will be apparent from a reading of the

following description in conjunction with the accompanying drawings which illustrate a preferred embodiment of the invention.

BRIEF DESCRIPTION OF THE DRAWINGS

In the drawings:

FIG. 1 is a longitudinal quarter sectional view showing a tool and packer assembly, according to a preferred embodiment of the invention, in the running position within a surrounding well conduit;

FIG. 2 is a longitudinal sectional view of the tool and well packer assembly of FIG. 1 shown in the set position;

FIG. 3 is a longitudinal quarter sectional view showing the upper portion of the tool and packer assembly of FIGS. 1 and 2 in the running position;

FIG. 4 is a longitudinal sectional view of the portion of the tool and well packer assembly shown in FIG. 3 in the first stage of setting the packer seal;

FIG. 5 is a longitudinal sectional view, similar to FIG. 4, showing the tool in a subsequent downwardly displaced position in which a portion of the tool has engaged a portion of the packer for actuating the seal and in which the pack-off means carried thereby has engaged the annular passage between the mandrel and the surrounding well packer supporting body;

FIG. 6 is a longitudinal sectional view, similar to FIGS. 4 and 5, showing the subsequent step in which pressure has been applied to the upper end of the pack-off means to release it for limited axial movement on the mandrel and to further compress the pack-off seal;

FIG. 7 is a longitudinal sectional view, similar to FIGS. 4-6, showing a subsequent stage in which the pack-off means has been displaced from engagement with the annular passage permitting graveling operations to proceed;

FIG. 8, taken along line 8-8 of FIG. 3, is a cross sectional view of a portion of the setting tool, according to a preferred embodiment of the invention;

FIG. 9, taken along line 9-9 of FIG. 5, is a cross sectional view of the setting tool illustrating the pack-off means prior to its release for limited axial movement on the mandrel; and

FIG. 10, taken along line 10-10 of FIG. 6, is a cross sectional view of the setting tool after release from the mandrel and slight axial displacement thereon.

DESCRIPTION OF A PREFERRED EMBODIMENT

Referring first to FIGS. 1 and 2 there is shown a liner, well packer and tool assembly A attached to the lower end of an inner well conduit or tubing string T within a surrounding well conduit or casing C. The assembly A comprises a tubular liner hanger body 11 at the lower end of which is threadingly connected a connector collar 12. The lower end of connecting collar 12 may be threadingly received in the upper end of a tubular liner 13. Liner 13 may be of the type conventionally employed in gravel packing operations having slots or perforations (not shown) in its walls through which fluid may pass, but preventing the passage of particulate materials above a predetermined size. The lower end of the liner 13 may be closed by a plug (not shown). The liner is normally positioned so that it is surrounded by the zone or formation from which the well will produce. After graveling operations the petroleum depos-

its from the formation will first filter through the gravel pack then pass through the liner 13 into the production string to the surface of the well.

The upper end of the liner hanger body 11 is internally threaded to receive the lower end of the tubular supporting body 14 of a well packer. Carried on the supporting body 14 is an annular packer seal 15 disposed between a pair of setting cones or expanders 16 and 17. Both conical expanders 16 and 17 are slideable on the exterior of packer body 14. However, seal 15 and conical expanders 16 and 17 are prevented from premature displacement by a lower snap ring 18 and shear pin 19 (see FIG. 3). Threadedly attached to the upper end of packer body 14 is an annular ring 20 from which depends a plurality of resilient arms 21 at the ends of which are toothed slips 22. The slips 22 are adapted to slide over conical expanders 17 in response to relative motions between packer body 14 and cone 17. Another set of resilient arms 23 and slips 24 are attached to a cylinder 25 and the slips 24 are adapted to slide over the conical surface of cone 16 in response to movement of cylinder 25 relative to packer body 14.

The cylinder 25 surrounds the upper end of liner hanger body 11 in a telescopic sliding fit and is initially seated in its lowermost position on an annular shoulder 26 of liner hanger body 11. A shear pin 27 serves to temporarily secure the cylinder 25 to liner hanger body 11 in this lowermost position. A seal ring 28 is mounted in an appropriate groove on hanger body 11 to form a slideable fluidtight seal between the hanger body 11 and cylinder 25. The bore of cylinder 25 is reduced at its upper end to form a cylinder head 29 which is disposed in a close sliding fit about the exterior of packer body 14. An annular seal 30 creates a slideable fluidtight seal between the cylinder head 29 and packer body 14. A variable volume annular chamber 31 is provided between cylinder head 29 and the upper end of the liner hanger body 11 and is in communication with an annular space 32 provided by clearance between the exterior of the upper end of the hanger body 11 and the interior of cylinder 25. Annular space 32 and the variable chamber 31 communicate with one or more ports 33 extending radially through the wall of hanger body 11 at a point above seal ring 28. Ports 33 communicate with a pressure fluid supply, as will be described hereafter.

Concentrically disposed within the packer body 14, leaving an annular space 34 therebetween, is a tubular mandrel 35 which makes up a part of the running tool of the assembly A. The upper end of mandrel 35 is threadedly received within a coupling K by which the entire assembly A is connected to the tubing string T. A shoulder ring 36 rotatably surrounds the upper end of mandrel 35 and is maintained thereon by a snap ring 37. A roller bearing 38 also surrounds the upper end of mandrel 35 and is disposed between the lower end of coupling K and shoulder ring 36. A cylindrical sleeve or collar 39 is attached to shoulder ring 36 and, as will be more fully understood hereafter, is adapted to rest on the upper end of annular ring 20 to transmit the weight of the tubing string T to the packer body 14 when the mandrel 35 and tubing string T are lowered sufficiently. Because of the rotational mounting of ring 36 and bearing 38 mandrel 35 may be rotated when sleeve 39 engages ring 20 without disturbing the position of sleeve 39. Also mounted on mandrel 35 is a

pack-off assembly 40, the details and function of which will be more fully described hereafter.

Near its lower end the mandrel 35 may be provided with a cross-over head which may comprise cylinder 41 connected to mandrel 35 by segments or lugs 42 through which passages 43 are provided, including ports 44 in mandrel 35 and ports 45 in cylinder 41, providing fluid communication between the interior of mandrel 35 and the exterior of cylinder 41. As can be seen from the drawings, mandrel 35 terminates at a point above a connector coupling 46 so that an annular opening 48 communicates with the passageway 49 formed between cross-over head cylinder 41 and the lower end of mandrel 35.

The lower end of cross-over head cylinder 41 is 15 threadedly attached to the reducer coupling 46 to which is threadedly connected a flow tube 47. Although it is not shown, the flow tube 47 is open at its lower end and extends through the bore of liner 13 to a point adjacent to the lowermost slots or perforations (not shown) of liner 13.

A tubular releasing sleeve 50 is concentrically interposed between the cross-over head and the inner wall of hanger body 11. This sleeve 50 is normally slidable axially within hanger body 11, but is temporarily held against movement in its uppermost position by means of a shear screw 51 which extends through the wall of hanger body 11 into the sleeve 50. At its lower end the exterior of releasing sleeve 50 is reduced in diameter to provide an annular shoulder 52 adapted to receive the upper end of a coiled compression spring 53. The lower end of spring 53 similarly surrounds a reduced diameter portion of coupling 12 exerting a force against an annular shoulder 12a. The spring 53 serves to bias the releasing sleeve 50 toward its uppermost position after shear screw 51 has been broken, as will be subsequently described. The upper end of releasing sleeve 50 is adapted to abut the lower end of packer body 14 when the releasing sleeve is in its uppermost position, as illustrated in FIG. 1. A longitudinal groove 54 is formed in the outer wall of the releasing sleeve 50, extending from a point above shear screw 51 for a short distance, and is adapted to receive an indexing screw 55 which projects inwardly from the wall of hanger body 11 to prevent relative rotation between releasing sleeve 50 and hanger body 11, yet permitting limited relative axial movement therebetween after shear screw 51 has been released. An annular seal ring 56 is disposed between the exterior of releasing sleeve 50, just above shoulder 52, and the interior of hanger body 11 to form a fluidtight slidable seal between the lower portion of releasing sleeve 50 and hanger body 11. Similar seal rings 57 and 58 are provided between releasing sleeve 50 and hanger body 11 on opposite sides of an annular space 59 formed by the reduction of the exterior of releasing sleeve 50, to form fluidtight slidable seals with the bore of hanger body 11. The releasing sleeve 50 is also provided with ports 60 which may provide a continuation of passage 43 in the cross-over head 41.

A section of coarse threads 61 may be provided on the upper interior of releasing sleeve 50 for connection with complimentary threads formed on the exterior of cross-over head 41 near its upper end. These threads are provided to permit release of the cross-over head 41, mandrel 35 and flow tube 47 from the assembly A at a suitable stage in the operations, as will be subse-

quently described. Seal rings 62 and 63 are provided between the cross-over head and releasing sleeve 50.

Passages 43, including ports 44, 45 and 60, provide fluid communication between the interior of mandrel 35 and the annular space or channel 59 surrounding the upper end of releasing sleeve 50. Axial passage 49, including annular port 48, provides fluid communication between the interior of mandrel 35, the annular space 34, surrounding the mandrel within packer body 14, and the annular space B between casing C and tubing string T.

A sleeve valve 64 is mounted in the bore of mandrel 35 for controlling flow through these passages 43 and 49. The sleeve valve 64 includes a tubular body 65 which is slidably disposed in the bore of mandrel 35 and is provided at its upper end with a frusto-conical seat 66 for reception of a suitable closure member, such as plug P, as in FIG. 2. At a point intermediate its ends, the sleeve body 65 is provided with a plurality of radial ports 67 which are adapted to be moved into and out of registration with annular port 48. The portion of the valve body 65 above port 67 serves to open and close ports 44, or the inner ends of fluid passages 43, depending upon the position of the valve body, as will be subsequently described.

As shown in FIG. 1, the sleeve body 65 is in its uppermost position in which both passageways 43 and 49 are closed. Seal rings 68, 69 and 70 are disposed between the sleeve body 65 and the bore of mandrel 35 to provide sliding seals for isolating the passages 43 and 49 in both open and closed positions. A snap ring 71 is suitably mounted on the exterior of sleeve valve body 65 at a point below seal ring 70 and is adapted to engage a tapered surface 72 at the upper end of reducing coupling 46 to releaseably lock the sleeve valve 64 in the uppermost position of FIG. 1. It will be understood that by exertion of sufficient downward pressure on the upper end of valve body 65, snap ring 71 can be compressed sufficiently to force it inwardly and allow the sleeve valve body 65 to be moved downwardly. A snap ring groove 73 is provided within reducer coupling 46 and is adapted to receive the snap ring 71 when the sleeve valve has traveled downwardly a sufficient distance to place the snap ring 71 opposite groove 73, as in FIG. 2. In this position the sleeve valve will be locked so as to place ports 67 in registration with annular port 48 and the upper end of the sleeve valve will have moved to a point below port 44 thereby opening the latter for communication with flow passage 43 of the cross-over head.

Referring now also to FIG. 3 a more detailed description of the packoff assembly 40 and the upper portion of mandrel 35 will be given. The pack-off assembly 40 may comprise a composite body 80 which surrounds the upper portion of mandrel 35 in an axially sliding fit. The body 80 may be conveniently formed of upper and lower tubular sections threadedly connected at 81 to facilitate the assembly of an annular pack-off seal 82. A seal ring 83 may be disposed between the interior of body 80 and the exterior of mandrel 35 to provide a fluidtight sliding seal therebetween. The pack-off assembly 40 may initially be maintained in the position shown in FIG. 3 by hold-down means which includes an annular retainer ring 84 engaging a corresponding annular groove 85 on the mandrel 35. The bore of the lower body section may be counterbored to provide a shoulder 86 against which one end of the ring 84 rests. At-

tached to the upper body section by a shear screw 87 is a ring 88 which abuts the opposite end of retainer ring 84 preventing the pack-off assembly 40 from being displaced axially downward until a sufficient force is applied to break the shear screw 87. It can be understood that if a sufficient force is applied to the upper end of body 80 shear screw 87 will be broken allowing the body 80 to move downwardly relative to ring 88 and retainer ring 84 until snap ring 84, which is radially compressed, is allowed to expand into the space vacated by ring 88 (see FIG. 6). The hold-down means also comprises friction means which may include an expandable ring 89 having downwardly directed teeth on its interior which correspond with upwardly directed teeth 90 on the exterior of mandrel 35. The purpose of the friction means is to allow movement of the pack-off assembly 40 in an upward direction, relative to mandrel 35, while restricting the downward movement thereon, as will be more fully understood hereafter. The pack-off assembly is also provided with an inwardly directed annular shoulder or flange 91 and flow ports 92 the function of which will be understood hereafter.

The body 80 of the pack-off assembly may reciprocate, unless prevented from doing so by the hold-down means within the annular space 93 bounded on the interior by mandrel 35 and on the exterior by sleeve 39. The sleeve 39 also includes ports 94 which provide communication between the upper end of annular area 93 and the annulus B between casing C and tubing string T. The sleeve 39 also includes another set of ports 95 which may provide flow communication between the annular passage 34 within packer body 14 and the annulus B above the sleeve 39. The outside diameter of sleeve 39 is less than the inside diameter of casing C allowing free passage of fluids on the exterior of sleeve 39.

The pack-off assembly 40 and the sleeve 39 make up a considerable part of the improvements in the present invention over the prior art. Except for these components, a change in the well packer construction and minor differences in the remaining portion of the assembly A, it is similar to the liner, well packer and tool assembly described in the aforementioned U.S. Pat. No. 3,072,204 and operates in much the same fashion, but with the highly significant ability to test the well packer seal and to apply additional sealing forces thereto.

In operation the assembly A is run through the casing C attached to the lower end of tubing string T as shown in FIG. 1. The assembly is lowered within casing C to a point where the liner 13 is substantially surrounded by the producing formation (not shown). When the assembly has obtained this position, circulation of washing fluid may be initiated by pumping fluid down through the bore of tubing T, mandrel 35 and flow tube 47, the fluid flowing out the open end of flow tube 47, out the perforations (not shown) in liner 13 and thence upwardly to the surface of the well through the annulus B. Of course, circulation can be conducted while the assembly A is being lowered into the well. The washing fluid, circulated as described, may be employed to clean the liner 13 and to wash out the face of the formation to provide more capacity for the reception of gravel when the latter is introduced. It will also be seen that when the parts of the assembly are in the initial running in position, sleeve valve 64 will be positioned to close the entrance of passages 43 and 49 through the

cross-over head. Therefore, no fluid can pass from the interior of the cross-over head to the exterior thereof, except as it may flow down through the flow tube 47 and up past the assembly A through the annulus B.

When the assembly A has been lowered to the desired position in the well bore, a closure member, such as plug P, may be dropped through the tubing string and pumped down with fluid until it rests on the seat 66 at the upper end of sleeve valve 64, thereby closing off the portion of the bore of the string below the upper end of sleeve valve 64. As pressure is applied to the plug P, the snap ring 71 is compressed and the plug P is forced downwardly with sleeve valve 64 until the snap ring 71 engages the groove 73. At this point the entrance of passage 43 through ports 44 will be opened and ports 67 will be in registration with annular port 48 for entrance into passage 49.

The opening of passage 43 will then permit the pressure fluid to flow through port 60 in releasing sleeve 50, through the clearance 59 surrounding the upper end of releasing sleeve 50 and port 33 in hanger body 11, into the annular space 32 and variable annular chamber 31 beneath the cylinder head 29. When this pressure has obtained a magnitude great enough to shear screws 27 they will break, allowing cylinder 25 to move upwardly. This causes slips 24 to move upwardly and outwardly over the tapered surface of conical expander 16, wedging the slips 24 into gripping engagement with the wall of casing C and anchoring the packer body 14 and the liner string therebelow to the casing. Since, at this stage of operation, there is no other outlet from the interior of the tubing strings, except to cylinder 25, the fluid pressure thus exerted will act very quickly to anchor the slips. This position is best shown in the FIG. 4.

When the slips 24 have been anchored, the tubing string T is lowered sufficiently to bring sleeve 39 into contact with the upper slip ring 20 (FIG. 2 and 5) and sufficient weight is applied through the tubing string T to move the packer body 14 downwardly relative to the lower slips 24. Since the slips 24 are wedged between the casing C and expanding cone 16, they will remain stationary causing the packer seal 15 to be compressed between lower expander 16 and upper expander 17. When a sufficient force is applied the shear screw 19 will break allowing the expander 17 to move upward relative to hanger body 14 wedging the upper set of slips 22 into anchoring engagement with the casing C. See FIG. 5. Continued force causes the packing seal 15 to be expanded radially to form a fluidtight seal between the packer body 14 and the wall of casing C. The lower slips 24 maintain the seal on the lower side while the upper slips 22 maintain the seal from above and prevent upward movement of the well packer. At this stage of operations the pack-off assembly 40 will have sealingly engaged the annular passage 34 between mandrel 35 and packer body 14, blocking flow from passage 34 into the annulus B.

Lowering of the tubing T in the manner just described will apply sufficient downward pressure on the cross-over head 41 and releasing sleeve 50 to break shear screws 51, allowing these components to move downwardly relative to the hanger body 11, spring 53 being compressed by this movement. See FIG. 2. This downward movement of the cross-over head and releasing sleeve 50 will bring passages 43 and port 60 into registration with discharge ports 11a in the hanger

body 11. Were it not for pack-off assembly 40 fluid circulation could then be developed between tubing string T and annulus B by circulation through passage 43, ports 60 and 11a through the liner 13 and flow tube 47, through axial passage 49 in the cross-over head and annular passage 34. In fact, with the prior art apparatus, graveling operations would proceed by circulating particulate laden fluid in this manner without first testing the packer seal 15.

With the improvement of the present invention, the packer seal 15 may be tested at this stage of operations to assure that an effective seal has been obtained before graveling takes place. If the seal is fluidtight graveling may proceed, but if it is not remedial steps can be taken without the complications which necessarily arise after gravel has been deposited around the liner 13.

With the assembly A in the positions of FIG. 2 and 5 testing may proceed by applying test pressure to the annulus B. The pressure fluid is applied through ports 94 and 95 to the upper end of the pack off assembly 40. When a sufficient pressure differential exists, shear screw 87 will be broken allowing the pack-off body 80 to move downwardly relative to mandrel 35 until retainer ring 84 expands into the space vacated by ring 88 as shown in FIG. 6. At about this point the tapered shoulder 80a of the pack-off assembly will contact slip ring 20 causing additional downwardly directed forces to be applied to packer body 14 and upper slips 22, further setting the seal 15 if so desired. Then test pressure may be maintained for a sufficient time to determine that a leak does not exist in the well packer seal. If a leak does exist the pressure will drop and there will be a corresponding increase in the pressure or fluids in the tubing string T.

Once it has been determined that the packer seal 15 is properly set the pack-off assembly 40 must be displaced axially upward relative to mandrel 35 to allow graveling operations to proceed. This is accomplished by relieving the pressure in annulus B and applying a pressure to the lower end of pack-off assembly 40 through tubing string T passage 43, ports 60 and 11a, liner 13, flow tube 47 and passage 49. When this pressure is sufficiently high, the pack-off assembly 40 will be forced upwardly to the position shown in FIG. 7. As the pack-off assembly 40 moves upward the ring 88 contacts the bottom of friction ring 89 causing it to expand and contract as its downwardly directed teeth ride over the upwardly directed teeth 90 of mandrel 35. Once the pack-off assembly has been moved to the upper position it is restricted from downward movement by the engagement of body shoulder 91 with the upper end of friction ring 89. Since the teeth on the friction ring 89 are directed downwardly and the teeth 91 on mandrel 35 are directly upwardly the ring 89 will not expand and consequently will prevent the re-engagement of the pack-off assembly 40 with the annular passage 34.

Once the pack-off assembly 40 is displaced to the position shown in FIG. 7, fluid circulation may be re-established between the annulus B and tubing string T through the mandrel cross-over head passages and the inner connecting ports and passageways. Circulation of fluid in this manner may be employed to additionally wash out or cavitate the face of the producing formation, providing an enlarged capacity for gravel in order

to increase the thickness and volume of the supporting body of gravel.

Then gravel or particulate matter such as coarse sand may be introduced with the fluid flowing into the annulus between the formation and the liner 13, being deposited there since the particulate matter selected would be of a size so as not to pass through the perforations (not shown) of liner 13. However, the fluid accompanying the gravel or particulate matter would be strained through the gravel and would flow through the perforations, through the lower end of flow tube 47, upwardly through passages 49 and 34 into the annulus B where it would be returned to the surface. If desired the assembly could be back washed by simply reversing circulation through the annulus B and out tubing string T.

Once gravel packing has been completed, as described, the mandrel 35 along with pack-off assembly 40, the cross-over head and flow tube 47 may be withdrawn. This is accomplished by picking up on the tubing string sufficiently to raise the port 60 of releasing sleeve 50 out of registration with discharge ports 11a, thereby cutting off the circulation of fluid to the annulus below the packer seal 15. With the tubing string in its elevated position, the tubing string may be rotated a sufficient number of turns to release the threaded connection 61 between the cross-over head 41 and releasing sleeve 50. The tubing string T, including mandrel 35, pack-off assembly 40, the cross-overhead and flow tube 47, can then be withdrawn from the hanger and packer structure. When these elements are removed, spring 53 is released from its previously compressed position to urge the releasing sleeve 50 to its uppermost position, as in FIG. 1, thereby maintaining ports 60 out of registration with discharge ports 11a and preventing passage of fluid from the producing formation into the remaining structure, unless the fluid first passes through the perforations of line 13.

Once the tubing string 10 and its connecting components have been withdrawn, a production tubing string may be installed. This operation is entirely conventional and forms no part of the present invention.

Thus it can be seen that the present invention provides an improved liner, well packer and tool assembly for graveling operations which permit testing of the packer seal prior to graveling. In addition it provides a means by which the seal may be more firmly set. Furthermore the anchoring means assures a firm set without having to depend upon the weight of the liner as with packer seals of the prior art.

Although the pack-off assembly 40 and the related sleeve 39 have been described primarily for use with graveling operations, they are not so limited. The invention could very easily be adapted to test other types of well packers and to apply additional forces for setting such packers. In fact many variations of the invention will be apparent to those skilled in the art. The specification, including the abstract, and the drawings are not to be taken as limiting the invention in any way. It is intended that the scope of the invention be limited only by the claims which follow.

We claim:

1. Apparatus for testing a well packer having a supporting body anchored to a surrounding well conduit and on which is carried a seal member for forming a fluidtight seal between said conduit and said supporting body, said apparatus comprising:

- a. an inner well conduit concentrically disposed within said surrounding well conduit to form a first annular passage therebetween;
- b. a tubular mandrel connected to said inner conduit for disposition within said supporting body to form a second annular passage in fluid communication with said first annular passage and the bore of said well beneath said packer seal;
- c. annular pack-off means carried by said mandrel axially movable from a first position above said second annular passage to a second position sealingly engaging said second flow passage and preventing flow of fluid between said bore of said well beneath said packer seal and said second annular passage;

- 10
- d. said pack-off means comprising a cylindrical sleeve member on which is carried an annular seal for engaging said supporting body when in said second position, said sleeve member being mounted on said mandrel for limited axial movement relative to said mandrel.

2. Apparatus as set forth in claim 1 in which said sleeve member is affixed to said mandrel by holdown means, said holdown means being adapted to release said sleeve member for said limited axial movement.

3. Apparatus as set forth in claim 2 in which said holdown means comprises retainer means on said mandrel and said sleeve member responsive to pressure applied to one end of said sleeve member to effect said sleeve member release.

4. Apparatus as set forth in claim 3 in which said retainer means comprises a snap ring carried by one of said mandrel and sleeve member engaging an annular groove in the other.

5. Apparatus as set forth in claim 2 in which said holdown means comprises cooperable friction means on said mandrel and said sleeve member permitting axial movement of said sleeve member in one direction while restricting movement in the opposite direction.

6. Apparatus as set forth in claim 5 in which said friction means comprises an expandable and contractable annular ring with teeth on one of said mandrel and sleeve member engageable with corresponding teeth on the other.

7. Apparatus as set forth in claim 1 in which said mandrel is axially movable relative to said supporting packer body, stop means being carried by said mandrel and engageable with said supporting packer body to limit said axial movement in one direction.

8. Apparatus as set forth in claim 7 in which said mandrel is initially attached to said well packer, said attachment being releasable to permit downward axial displacement of said mandrel from said initial position to a position in which said stop means engages said well packer.

9. Apparatus as set forth in claim 7 in which said pack-off means is responsive to pressure in said first annular passage for further axial movement in the same direction relative to said supporting packer body while said mandrel remains stationary.

10. In combination a gravel packer and running tool comprising:

- a. a tubular body having a perforate liner attached thereto;
- b. resilient seal means carried by said body;
- c. anchor means carried by said body operable to anchor said seal means to a surrounding well conduit

and to acuate said seal means for sealing between said body and said surrounding conduit;

- d. an inner well conduit concentrically disposed in said surrounding well conduit;
- e. a tubular mandrel attached to said inner well conduit and disposed within said body to provide first and second axially extended flow passages for conducting fluids between upper and lower points above and below said seal means;

15

- f. cross-over flow passage means extending from said first flow passage and opening externally of said tubular body at a point below said seal means to provide fluid communication between said first and second flow passages through said perforate liner;

- and
- g. pack-off means carried by said tubular mandrel for limited axial movement thereon and movable from a first position permitting fluid flow through said second flow passage to a second position sealingly preventing flow through said second flow passage.

11. The combination of claim 10 in which said second flow passage comprises an annular space surrounding said tubular mandrel within said tubular body, said pack-off means including a first seal member for engagement with the outer confines of said annular space, a second seal member being disposed between said packoff means and said tubular mandrel providing a sliding sealing fit therebetween.

12. The combination of claim 11 in which said pack-off means comprises holdown means preventing premature axial displacement of said pack-off means relative to said tubular mandrel.

13. The combination of claim 12 in which said pack-off means is axially displaceable with said mandrel to sealingly engage and block said second flow passage.

14. The combination of claim 13 in which said hold-down means comprises retainer means responsive to pressure applied to one end of said packoff means to release said pack-off means for said limited axial movement on said tubular mandrel.

15. The combination of claim 14 in which said hold-down means comprises friction means responsive to pressure applied to one end of said pack-off means to allow said limited axial movement in one direction while restricting movement in the opposite direction.

16. The combination of claim 13 comprising stop means carried by said mandrel and engageable with a portion of said gravel packer to limit axial movement of said mandrel in one direction relative to said tubular body.

17. The combination of claim 16 in which said stop means is engageable with said anchor means to apply additional sealing forces to said resilient seal means.

18. The combination of claim 10 in which said second flow passage comprises an annular space bounded on the outside by said tubular body and on the inside by said tubular mandrel, said pack-off means comprising a cylindrical sleeve member having a first seal member for sealingly engaging said tubular body, a second seal member being disposed between said cylindrical sleeve member and said tubular mandrel to provide a sliding sealing fit therebetween, said cylindrical sleeve member being responsive to pressure applied to one end thereof to effect axial displacement of said cylindrical sleeve member relative to said tubular mandrel.

60

65

19. The combination of claim 18 in which said cylindrical sleeve member is initially prevented from said axial displacement relative to said tubular mandrel by holdown means, said holdown means being responsive to a predetermined pressure applied to said one end of said cylindrical sleeve member to release said cylindrical sleeve member for said limited axial movement while sealingly engaging said annular space.

20. The combination of claim 19 in which said holdown means comprises friction means responsive to pressure applied to the opposite end of said cylindrical sleeve member to displace said cylindrical sleeve member from said annular space and preventing reengagement thereof.
